(57) **CLAIM**

The ornamental design for a vehicle rim, as shown and described.

DESCRIPTION

FIG. 1 is a front view of a vehicle rim showing my new design;

FIG. 2 is a right perspective view thereof;

FIG. 3 is a left perspective view thereof;

FIG. 4 is a right side view thereof;

FIG. 5 is a left side view thereof;

FIG. 6 is a top view thereof; and,

FIG. 7 is a bottom view thereof.

The broken lines and the portions of the design shown within depict portions of the vehicle rim that form no part of the claimed design.
